UNITED STATES PATENT OFFICE.

WILLIAM BENS, OF PROVIDENCE, RHODE ISLAND, ASSIGNOR TO WIENER BROTHERS, OF NEW YORK, N. Y.

DESIGN FOR A HANDLE FOR BUTTON-HOOKS OR SIMILAR ARTICLES.

SPECIFICATION forming part of Design No. 29,088, dated July 26, 1898.

Application filed July 1, 1898. Serial No. 684,993. Term of patent 3½ years.

To all whom it may concern:

Be it known that I, WILLIAM BENS, a citizen of the United States, residing in the city and county of Providence, State of Rhode Island, have invented and produced a new and original Design for the Handles of Button-Hooks or Similar Articles, of which the following is a specification, reference being had to the accompanying drawing, forming part thereof.

The drawing shows my design applied to the handle of a button-hook.

Said design consists in the novel configuration and ornamentation of the handle, as hereinafter described.

The lower end of the handle *a* is an unornamented cylindrical band. Therefrom the handle expands outward and upward with an intermediate swell *b* to its top *c*, which is crowned by converging scroll ornamentations *h h* and a centrally-supported tip *d*, formed by a single foliated scroll. The top ornamentation is completed by single balls *k k* on either

side of the scroll *d*. From the junction of the scrolls *h h* depends a fleur-de-lis *m*. Rows 25 of spherical beading *e e* on either side follow the contour of the handle, diminishing in size as they approach the top and bottom thereof. A small floral ornament *g* is centrally located upon the handle, flanked by foliates *z z*, 30 whence extend a raised beading *x x* upward and downward, bounding the central panels *o o*.

Having thus described my invention, I claim as new and desire to secure by Letters 35 Patent—

The design for the handle of button-hooks and similar articles herein shown and described.

In witness whereof I have hereunto set my hand.

WILLIAM BENS.

In presence of—

HORATIO E. BELLOWES,
BENJ. NUSSBAUM.
